SAFETY RAZOR BLADE

Application filed December 21, 1931, Serial No. 582,335, and in Germany July 2, 1930.

Razor blades are clamped for use in a safety razor. By tightening up an abutment to a greater or less extent by means of the handle of the razor, the blade is pressed 5 more or less firmly against the comb or guard of the razor. Under these circumstances the cutting edges of the blade are at a greater or less distance from the comb according to the degree of bending of the blade. If the 10 abutment is firmly tightened up, the cutting edges bear comparatively closely on the guard. In such a case shaving is particularly safe, since the blade is firmly clamped in the razor, and the user will not cut himself. 15 There is however the disadvantage that the blade does not catch particularly well. If on the other hand the abutment is moved away from the guard, the cutting edges of 20 the blade rise off the guard in consequence of the elastic properties of the blade. In this case the blade catches particularly well. There is however the disadvantage that the blade is liable to cut into the skin, since it vibrates during the shaving. 25 The blades are moreover in the course of manufacture stamped out of a long steel strip, or broken after the hardening of this strip at a so-called breaking mark. Since the 30 steel strip is produced by rolling, the fibres of the metal extend in the longitudinal direction therein, and therefore in the blades made therefrom, and the stiffness of the blade in the transverse direction is comparatively small. 35 These disadvantages are obviated by the razor blade according to the present invention, a blade being provided which can be firmly clamped between the parts of the razor, and in which the cutting edge is far 40 enough away from the guard comb to enable the individual hairs to be reliably seized. The razor blade according to the invention is moreover particularly well stiffened in the transverse direction, so that even in the event 45 of it not bearing completely upon the comb, it is not so liable to vibrate and therefore to cut into the skin.

The invention is diagrammatically illustrated by way of example in the accompanying drawing, in which

Figure 1 is a view of a razor blade according to the invention,

Figure 2 is a section on the line II—II in Fig. 1, on a greatly enlarged scale,

Figure 3 is a view of another form of construction of the razor blade according to the invention, and

Figure 4 is a section on the line IV—IV in Fig. 3.

According to the invention the blade *b* of a flexible leaf-shaped razor blade is stiffened by hammering or pressing in such a way that projecting elements *a* are produced. At *c* is indicated how the projections are separated from one another by clear boundary lines. Such a blade is immediately ready for use in shaving, and has the advantage hereinbefore indicated that the blade can be firmly clamped between the parts of the razor, but nevertheless cuts satisfactorily, and no vibrations of the blade take place.

In a further particularly advantageous constructional form the projections *a* are partly eliminated again by pressure or rolling, as indicated at *a'*. At *c'* it will be seen how the lines of separation originally pressed out have been flattened so that they no longer stand out so sharply. Owing to the elimination of the projections *a* and the flattening of the lines of separation, a further stiffening of the blade in the transverse direction is produced. Since the blade according to the invention is more resistant, it is possible to manufacture it from a cheaper material, which otherwise could not be employed at all for the manufacture of razor blades of such a high quality. In this way it is possible to reduce the price of a razor blade. A further advantage resides in the fact that the hardness can be increased, by a lower starting temperature for example, without running any risk of the blade breaking. Owing to the greater hardness, however, a better cutting power and a longer cutting life of the blade are obtained, or in other words an improvement in the cutting properties of the blade.

The invention is of course not restricted to blades with fastening holes of the kind illustrated but can also be employed with par-

ticular advantage in the case of those so-called long-hole blades, in which either the fastening holes are connected by means of a slot occupying the entire central portion, or in which, instead of the fastening holes, a slot extending over the central portion of the blade is provided, or in which this slot extends even beyond the region of the outer fastening holes. In such blades with an elongated hole the space e of the blade, located between the outer ends of the slot and the end edge d , is also preferably provided with such pressed or hammered elements, for the purpose of yielding good transverse stiffness of the blade just in the comparatively narrow portion of the blade by which the halves of the blade are held together.

What I claim is:—

1. A safety razor blade having uniformly arranged small depression areas covering the surface adjacent the cutting edge, said depression areas forming separate and independent raised boundary edges extending inwardly from the cutting edge.
2. A safety razor blade having uniformly arranged small depression areas covering the surface of the blade and forming a repeated pattern, adjacent depression areas being separated by independent and clear boundary lines extending inwardly of the cutting edge.
3. A safety razor blade having uniformly arranged small depressions on the surface of the blade, the depressions being separated from one another by clear boundary lines, said boundary lines being flattened to form a flattened surface.

In testimony whereof I affix my signature.

ADOLF LÜBBERTSMEIER.
